(57) **CLAIM**

The ornamental design for a bus barrier door, as shown and described.

DESCRIPTION

FIG. 1 is a rear perspective view of a first side of a bus barrier door of the present invention.

FIG. 2 is a front perspective view of the first side of the bus barrier door of FIG. 1.

FIG. 3 is a rear perspective view of a second side of the bus barrier door of FIG. 1.

FIG. 4 is a front perspective view of the second side of the bus barrier door of FIG. 1.

FIG. 5 is an elevational view of the first side of the bus barrier door of FIG. 1.

FIG. 6 is an elevational view of the second side of the bus barrier door of FIG. 1.

FIG. 7 is an elevational view of a front end of the bus barrier door of FIG. 1.

FIG. 8 is an elevational view of a rear end of the bus barrier door of FIG. 1.

FIG. 9 is a top plan view of the bus barrier door of FIG. 1.

FIG. 10 is a bottom plan view of the bus barrier door of FIG. 1; and,

FIG. 11 is an elevational view of the first side of the bus barrier door of FIG. 1 showing the bus barrier door installed in a bus. The broken lines in the drawings illustrate the environment of the bus barrier door and form no part of the claimed design.
